CENTRIFUGAL APPARATUS FOR IMPREGNATING ONE MATERIAL WITH ANOTHER

Ernest G. Kochli, Brooklyn, N. Y., assignor to Applied Sugar Laboratories, Inc., New York, N. Y., a corporation of New York

Application May 14, 1942, Serial No. 442,924

7 Claims. (Cl. 210—67)

1

This invention relates to apparatus adapted for the dispersion of a liquid throughout the mass of a solid capable of being separated from a liquid in centrifugal apparatus.

It is an object of this invention to provide apparatus which may be employed generally for the distribution or dispersion of a liquid throughout a mass of solid material in a centrifuge, which solid material is capable of separation from its mother liquor by centrifugal action.

It is a further object of the invention to apply the liquid to be dispersed automatically during a predetermined period in the speed and current cycles of a multi-speed motor driving a centrifuge.

The principles of this invention will be defined in the claims appended hereto and will be illustrated by reference to the accompanying drawings, in which:

Fig. 1 is a diagram showing illustrative speed and current cycles and the manner in which these cycles are taken advantage of in accordance with the present invention;

Fig. 2 is an illustrative circuit layout showing a circuit which may be employed in practicing the present invention; and

Fig. 3 is a perspective view showing a centrifugal and multi-speed motor and various flow lines and parts associated therewith.

Referring first to the diagram of Fig. 1, the ordinates of the curve marked "speed" represent variations in speed and the abscissae the time of a typical speed cycle. The ordinates of the curve marked "current" show variations in current and the abscissae represent increments of time of a typical current cycle corresponding to the speed cycle. The description of Fig. 1 will be stated in terms of the application of the present invention to the distribution of a vitamin solution throughout the mass or mantle of sugar crystals in a centrifuge, although it will be understood that the invention is not limited to the distribution of any particular liquid throughout the mass of any particular solid so long as the solid is one which is capable of treatment in a centrifugal for the purpose of separation thereof from mother liquor, washings and the like.

In accordance with the present invention the vitamin solution, emulsion or the like may be applied to a mass of sugar in a centrifugal, that is, after the green syrup has been separated from the sugar and following predetermined washing and drying periods.

In accordance with the invention of my United States Patent No. 2,244,652, issued June 3, 1941, wash water may be automatically applied to the

2

mantle of sugar in a centrifuge at a predetermined maximum speed thereof, thereby establishing a predetermined purging period to remove green syrup and the wash water may be automatically applied during any desired or predetermined washing period which may also be followed by an automatically predetermined drying period.

The present invention may be advantageously employed in conjunction with the application of 10 the invention of said United States Patent No. 2,244,652 and the cycles shown in Fig. 1 typify and illustrate a conjoint use of the present invention and that of said United States Patent No. 2,244,652 in those cases where the centrifuge 15 is driven by a two-speed motor.

Referring again to Fig. 1, the portion 1A of the curve represents the in-rush current when the centrifuge is started on the low speed circuit. The portions 2A represent the current 20 changes during the change from low speed to high speed. The portion 3A shows the decrease of current in the high speed circuit as the basket picks up speed and gradually attains maximum speed, the corresponding part of the speed curve 25 being represented by the numeral 4A. At any predetermined points 5A and 5a on the current and speed curves, respectively, wash water may be automatically applied in accordance with United States Patent No. 2,244,652, thus establishing 30 the end of the purging period and the beginning of the washing period. The duration of the latter may also be predetermined in accordance with said United States Patent No. 2,244,652 and followed by a predetermined drying 35 period, as shown in Fig. 1.

At a predetermined point 6A on the speed curve the speed of the motor is changed from high to low and the portions of the current curve marked 7A show the regenerative electrical effect 40 and the corresponding current change resulting from this shift from high to low speed. The regenerative effect of multi-speed motors and the accompanying speed changes therein are per se well known and need not be described in detail except to state that as a change is made from the high speed to the low speed circuit the current momentarily drops to zero and then increases again due to the generation of current by the motor as a result of the inertia or momentum of the centrifuge.

The present invention takes advantage of the current change accompanying this regenerative effect in order to automatically apply at a predetermined speed and during a predetermined period, to the mantle of solid material, for ex-

ample sugar, in the centrifuge, a liquid, for example a vitamin solution, to be dispersed in said solid material.

There are four variables to be controlled, to wit: (a) the quantity or mass of solid material in the centrifuge, e. g., sugar crystals; (b) the volume of liquid material, e. g., vitamin solution to be distributed; (c) the speed of the centrifugal; and (d) the time during which the vitamin solution is applied. When these variables are fixed the ultimate concentration of vitamins (for example) can be changed by changing the concentration of the vitamin in the solution applied to the sugar. Having fixed the variables (a) and (b), it then becomes necessary to make certain that the vitamin solution properly penetrates the mantle or annulus of sugar crystals from the inside surface thereof to the outside surface but not beyond. If the penetration of vitamin solution (or other liquid material) extends for only a fraction of the width of this annulus then the result would be a mixture of sugar containing no vitamin with sugar containing an unduly high concentration thereof. If the vitamin solution penetrates not only the entire width of the annulus but passes out beyond it, not only is the vitamin solution lost but the desired concentration thereof in the sugar would be lower than calculated. The desired distribution of vitamin solution then becomes a function of the speed of the centrifugal and the time during which the vitamin solution is applied to the sugar. At high speeds the necessary time is less than at low speeds.

It is therefore highly desirable to be able automatically to select the speed at which the vitamin solution is applied and automatically to predetermine the period of application, and the present invention automatically provides this control.

Furthermore, since the desired speed is automatically selected and the time of application automatically predetermined, uniformity from batch to batch results. It is of course possible to obtain these advantages by manual control but this necessitates extremely careful supervision and is therefore a relatively expensive operation. The present invention, since it accomplishes the necessary control automatically, greatly reduces the expense while at the same time assuring uniformly controlled satisfactory results.

Referring again to Fig. 1, the speed at which the vitamin solution, for example, is applied may be selected at any desired point on the portions of the current curve marked 7A and 7a, preferably at some point on the curve marked 7a, that is, while the current in the low speed circuit is decreasing and during the electrical braking effect which accompanies the regenerative effect.

The invention will further be described in connection with certain typical apparatus and the circuits therefor, as illustrated in Figs. 2 and 3.

The driving motor 1 illustratively shown in the drawings is of the two-speed line-start type, and the motor starter 2 is provided with a double throw contactor arrangement, operated through auxiliary relays for the automatic speed change.

When the remotely located 2-pole master switch 4 is closed, the pull-in coil 5 of the contactor 6 in the motor starter 2 will be energized, which closes the contactor and causes the motor 1 to start on the low speed winding 8.

After loading the sugar basket, with the motor running on low speed, the operator presses the remotely located 2-circuit "high-speed" push button 12 which energizes the coil 14 of the 3-circuit relay 16 and simultaneously the coil 17 of

the 2-circuit relay 18. The bottom contacts 20 of relay 16 open, thereby de-energizing the pull-in coil 5 of the low speed contactor 6 which in turn opens the power circuit of the low speed motor winding 8. The top contacts 22 of the relay 16 close, thereby energizing the pull-in coil 24 of the contactor 25 in the motor starter 2, which closes the contactor 25 and causes the motor to accelerate on the high speed winding 28. The middle contacts 30 of the relay 16 maintain the circuit to its coil 14 after the "high-speed" momentary contact push button 12 has been released.

The top contacts 32 of the 2-circuit relay 18 close and thereby maintain the circuit to its coil 17 after the "high-speed" momentary contact push button 12 has been released, and the bottom contacts 33 of relay 18 close the circuit to the coil 35 of the regeneration timing relay 36 provided with dash pot 38.

With the closing of the high speed contactor 25 the current transformer 40 connected in the high speed motor winding 28 becomes energized and the induced secondary current energizes the coil 41 of the "high-speed" current limiting relay 42, the contacts 44 of which are normally kept open by a lock-out device including lever 46 and plunger 48. The plunger or adjustable core 47 is so adjusted in relation to the coil 41 as to cause the closing of the contacts 44 when the speed of the motor has reached a selected and predetermined maximum (see 5a, Fig. 1) corresponding to a predetermined minimum current in the high speed motor winding (see 5A, Fig. 1) in accordance with the invention of my United States Patent No. 2,244,652.

Simultaneously the auxiliary contact 50 on the high speed contactor 25 closes and energizes the shunt solenoid coil 52, thereby actuating the current limiting relay lock-out device 46, 48. The closing of contacts 44 energizes the solenoid coil 54 of the wash water valve 56, as well as the motor 57 and clutch coil 58 in the wash water timer 59. The wash water valve thereby opens and the timer 59 initiates the washing period. The manually operated switch 61 is used to permit operation of the wash water valve independently of the timing mechanism 59.

Simultaneously with the initiation of the water spraying the coil 63 of the time-delay relay 64, provided with dash pot 65, actuating the gutter shift for the syrup segregation, becomes energized. After a predetermined time interval the relay contacts 68 close which energizes the solenoid coil 69 in the air valve 70, thus opening the said valve and admitting compressed air to the gutter shift mechanism 71. This need not be described in detail since it is substantially the same as described in my United States Patent No. 2,244,652. With the closing of the time-delay relay contacts 68 and the coil 73 of the maintaining relay 74 also becomes energized, which in turn closes its contacts 75 and keeps the air valve solenoid coil 69 energized for the remainder of the cycle.

After a predetermined time interval the contacts 76 in the water timer 59 close, thereby energizing the coil 78 of the wash water limiting relay 79 as well as the motor 81 and clutch coil 82 in the drying timer 83. The contacts 85 of the wash water limiting relay 79 open, which de-energizes the solenoid coil 54 thereby closing the spray water valve 56. With the opening of the water limiting relay contacts 85 the motor 57 in the water timer 59 will also be stopped. At this time, the end of the washing period and

4

the beginning of the drying period have been reached. After a predetermined time interval the contacts 87 in the drying timer 83 open. The motor 81 then stops and simultaneously the coil 14 of the 3-circuit relay 16 in the motor starter 2 is de-energized. The upper contacts 22 of this relay 16 open, thereby de-energizing the pull-in coil 24 of the high speed contactor 25, which in turn disconnects the motor high speed winding 28 from the line. At the same time the middle contacts 30 of the 3-circuit relay 16 open, thus breaking the coil-maintaining circuit. The bottom contacts 20 of this relay 16 close and the pull-in coil 5 of the low speed contactor 6 becomes energized thereby closing the power circuit to the low speed motor winding 8. This marks the end of the drying period and the beginning of the regeneration period indicated by 1A of Fig. 1.

The change-over from high speed to low speed initiates the regenerative braking action in the motor and with the closing of the low speed contactor 6 the current transformer 90 connected in the low speed motor winding 8 becomes energized. The induced secondary current energizes the coil 91 of the "low-speed" current limit relay 92, the contacts 93 of which are normally kept open by a lock-out device including lever 94 and plunger 95.

Simultaneously with the closing of the low speed contactor 6 the coil 35 of the regeneration timing relay 36 in the motor starter 2 is energized. This actuates the dash pot time-lagged relay 36 to close contacts 106 and open contacts 107 which determine the duration of the regeneration period as hereinafter more fully explained. Also, the coil 100 of the single circuit interlocking relay 101 becomes energized through the bottom contacts 20 of the 3-circuit relay 16. The energizing of coil 100 closes contacts 103, in a circuit including coil 104, which circuit can be completed only upon closing of contacts 103. The energizing of coil 104 retracts plunger 95 to permit operation of the core 109 of the relay 92 to initiate the period during which vitamin solution is to be applied (see Fig. 1).

At a predetermined current value which corresponds to a definite motor speed during the decelerating period the contacts 93 of the "low-speed" current limiting relay 92 close, thus energizing the valve solenoid coil 110 and opening the vitamin spraying valve 112. Simultaneously the motor 114 and the clutch coil 115 in the vitamin spray timer 116 become energized, which initiates and controls the vitamin spraying period or dispersion period (see Fig. 1).

The selection of the precise speed of the motor at which to initiate the application of the vitamin or other liquid to be dispersed may be controlled by adjusting the position of the core 109 in relation to the coil 91 since the closing of the contacts 93 at any selected current value in the transformer 90 corresponding to said selected speed depends upon said adjustment.

After a predetermined time interval the contacts 118 of the timer 116 close and the coil 120 of the vitamin spray limiting relay 121 will be energized, which results in the opening of the relay contacts 122 and in turn causes the de-energizing of the solenoid coil 110 and the closing of the vitamin spraying valve 112. At the same time the timer motor 114 will be stopped, which concludes the vitamin spraying period.

After a predetermined time interval the regeneration timing relay 36 in the motor starter 2

6

6 opens the bottom contacts 107, which de-energizes the pull-in coil of the low speed contactor 6 and causes the contactor to disconnect the low speed motor winding 8 from the power supply line 123. This marks the end of the regeneration period. Simultaneously the top contacts 106 in the timing relay 36 close, which energizes the solenoid coil 124 which operates the air valve 125 for the mechanical braking device 126 on the 10 brake drum 127 of the centrifuge motor 1.

After the machine has come to rest by mechanical braking the operator opens the 2-pole master switch 4 which de-energizes all remote control circuits and re-sets all relays and timers to their original "off" position.

While the specific description has referred to the application of the mechanism to the dispersion of a vitamin solution in a mass of sugar crystals, it will be clear that the said mechanism is applicable generally to the dispersion of a liquid in a mass of solid material separated from liquid material in a centrifuge, as stated at the beginning of this specification.

I claim:

- 23 1. In centrifugal apparatus adapted to impregnate sugar with a solution separable therefrom by centrifuging, the combination with a centrifuge and a variable speed motor having a high speed winding and a low speed winding; of valve
30 means for delivering solution to the sugar in said centrifuge, a first switch means adapted to be closed to energize the low speed winding of the motor to operate the centrifuge at a low speed, a second switch means adapted to be closed to
35 energize the high speed winding of the motor to operate the centrifuge at a higher speed, means for opening said first switch means coincidently with the closing of the second switch means, a first timer device adapted to open said second
40 switch means and coincidently close said first switch means after an interval of high speed operation of the centrifuge, thereby generating a reverse current in said low speed winding, a circuit energized by said reverse current adapted
45 to open said valve means, said valve means being normally closed during said low speed and high speed operation of the centrifuge, a second timer device actuated by said circuit for closing said valve means after an interval of time during
50 which solution is introduced to the sugar in the centrifuge to impregnate the same, and timing means actuated by said first timer device for opening said first switch means before any solution is spun out of the centrifuge, said motor being thereby disconnected from the low speed winding and the centrifuge coming to a halt.

2. In centrifugal apparatus adapted to impregnate sugar with a solution separable therefrom by centrifuging, the combination with a centrifuge and a variable speed motor having a high speed winding and a low speed winding; of valve
60 means for delivering solution to the sugar in said centrifuge, a first switch means adapted to be closed to energize the low speed winding of the motor to operate the centrifuge at a low speed, a second switch means adapted to be closed to
65 energize the high speed winding of the motor to operate the centrifuge at a higher speed, means for opening said first switch means coincidently with the closing of the second switch means, a first timer device adapted to open said second
70 switch means and coincidently close said first switch means after an interval of high speed operation of the centrifuge, thereby generating a reverse current in said low speed winding, a circuit

cuit energized by said reverse current adapted to open said valve means, said valve means being normally closed during said low speed and high speed operation of the centrifuge, a second timer device adapted to de-energize said circuit to close said valve means, and timing means actuated by said first timer device for opening said first switch means after impregnation of the sugar and before any solution is spun out of the centrifuge, said motor being thereby disconnected from the low speed winding and the centrifuge coming to a halt.

3. In centrifugal apparatus adapted to purify sugar and to impregnate the same with a vitamin solution separable therefrom by centrifuging, the combination with a centrifuge and a variable speed motor having a high speed winding and a low speed winding, each connectable in and disconnectable from a power circuit; of water supply means adapted to deliver wash water to the sugar in said centrifugal, means adapted to actuate said water supply means in response to predetermined high speed operation of the motor, wash water timer means adapted to render said water supply means inoperative after a predetermined time interval and adapted to initiate a drying interval during which the sugar in said centrifugal is dried, drying timer means actuated by said wash water timer means for limiting said drying interval by disconnecting the high speed winding from the power circuit and coincidentally connecting in the latter circuit the low speed winding after a predetermined interval of high speed operation, thereby to produce a regenerative current in the low speed winding power circuit, delivery means adapted to supply impregnating solution to the sugar in said centrifugal, regenerative current-responsive means adapted to actuate said delivery means, switch means energized by the circuit in the low speed winding for rendering said regenerative current-responsive means operative, solution timer means to render said delivery means inoperative after a predetermined time interval, and regenerative current timing means actuated by said drying timer means for disconnecting the low speed winding from the power circuit before said solution is spun out of the centrifuge, thereby shutting down operation of the motor.

4. In centrifugal apparatus adapted to impregnate sugar with a solution separable therefrom by centrifuging, the combination with a centrifuge and a variable speed motor having a high speed winding and a low speed winding, of a power circuit in which each of said windings is connectable and also disconnectable therefrom, switch means for connecting said high speed winding into the power circuit, timer means in a separate circuit responsive to the current in said high speed winding, said timer means being adapted to disconnect the high speed winding from the power circuit and coincidentally to connect in the latter circuit the low speed winding after an interval of high speed operation, thereby to produce a regenerative current in the low speed winding power circuit, delivery means to supply impregnating solution to the sugar in said centrifugal, and solution timer means to render said delivery means inoperative after a predetermined time interval, both said solution timer means and said delivery means being in a circuit separate from said low speed winding circuit and both being responsive to the regenerative current in the low speed winding circuit.

5. In a centrifugal apparatus adapted to im-

pregnate sugar with a solution separable therefrom by centrifuging, the combination with a centrifuge and a variable speed motor having a high speed winding and a low speed winding, of a power circuit in which each of said windings is connectable and also disconnectable therefrom, switch means for connecting said high speed winding into the power circuit, timer means in a separate circuit responsive to the current in said high speed winding, said timer means being adapted to disconnect the high speed winding from the power circuit and coincidentally to connect in the latter circuit the low speed winding after an interval of high speed operation, thereby to produce a regenerative current in the low speed winding power circuit, delivery means to supply impregnating solution to the sugar in said centrifugal, regenerative current-responsive means in a separate circuit from said low speed winding power circuit adapted to actuate said delivery means, means in the said low speed winding power circuit adapted to render said regenerative current-responsive means operative, and solution timer means actuated by said regenerative current-responsive means to render said delivery means inoperative after a predetermined time interval.

6. In centrifugal apparatus adapted to impregnate sugar with a vitamin solution separable therefrom by centrifuging, the combination with a centrifuge and a variable speed motor having a high speed winding and a low speed winding, of a power circuit in which each of said windings is connectable and also disconnectable therefrom, switch means for connecting said high speed winding into the power circuit, timer means in a separate circuit responsive to the current in said high speed winding, said timer means being adapted to disconnect the high speed winding from the power circuit and coincidentally to connect in the latter circuit the low speed winding after an interval of high speed operation, thereby to produce a regenerative current in the low speed winding power circuit, delivery means to supply impregnating solution to the sugar in said centrifugal, a first electrical circuit containing regenerative current-responsive means adapted to actuate said delivery means, a second electrical circuit adapted to render said regenerative current-responsive means operative, said second electrical circuit containing a transformer having its primary coil in the low speed winding circuit, and solution timer means in said first electrical circuit to render said delivery means inoperative after a predetermined time interval.

7. In centrifugal apparatus adapted to purify sugar and to impregnate the same with a vitamin solution separable therefrom by centrifuging, the combination with a centrifuge and a variable speed motor having a high speed winding and a low speed winding, of a power circuit in which each of said windings is connectable and also disconnectable therefrom, switch means for connecting said high speed winding into the power circuit, a water valve to supply wash water to the sugar in said centrifugal, a first electrical circuit containing means responsive to the current in said high speed winding for controlling said water valve, and also containing wash water timer means; a first transformer having its primary coil in the high speed winding power circuit and its secondary coil in said first electrical circuit, said water valve being adapted to open at predetermined values of the current in the high speed winding power circuit, a second electrical circuit

adapted to be closed by the action of the wash water timer means and means adapted upon the closing thereof to close said water valve, said second circuit including drying timer means adapted to disconnect the high speed winding from the power circuit and coincidentally to connect in the latter circuit the low speed winding after a predetermined interval of high speed operation of the centrifuge, thereby to produce a regenerative current in the low speed winding power circuit; a solution valve to supply impregnating solution to the sugar in said centrifugal, a third electrical circuit containing regenerative current-responsive means controlling said solution valve, and solution timer means; a second transformer having its primary coil in the low speed winding power circuit and its secondary coil in said third electrical circuit, said solution valve being adapted to open at predetermined values of regenerative current in the low speed winding power circuit, a fourth electrical circuit adapted to be closed by the action of the solution timer means and means adapted upon the closing thereof to

close said solution valve; braking means to stop the motor, means adapted to disconnect the low speed winding from the power circuit and to actuate said braking means.
